(57) **CLAIM**

The ornamental design for a telephone base, as shown and described.

DESCRIPTION

FIG. 1 is a perspective view of a telephone base;

FIG. 2 is a top plan view thereof;

FIG. 3 is a front elevational view thereof;

FIG. 4 is a left-side elevational view thereof;

FIG. 5 is a right-side elevational view thereof;

FIG. 6 is a rear elevational view thereof; and,

FIG. 7 is a bottom plan view thereof.

The broken line showings of FIGS. 4, 5, and 7 are for illustrative purposes only and form no part of the claimed design. The claimed surfaces continue up to, but do not include, the broken line showings.
